(57) **ABSTRACT**

A protective cap having a first cap and a second cap that are removably coupled together for use in short-term and long-term antimicrobial treatment of needleless connectors and access ports of an infusion system. The instant invention further provides a protective cap having a first cap and a second cap that each coupled to a different surface of a component of an infusion system, such as a syringe. The instant invention further provides a strip containing a plurality of disposable protective caps.

NEEDLELESS CONNECTOR AND ACCESS PORT DISINFECTION CLEANER AND ANTIMICROBIAL PROTECTION CAP

RELATED APPLICATIONS

This application is a continuation of U.S. patent application Ser. No. 16/832,807, filed Mar. 27, 2020, and titled NEEDLELESS CONNECTOR AND ACCESS PORT DISINFECTION CLEANER AND ANTIMICROBIAL PROTECTION CAP, which is a continuation of U.S. patent application Ser. No. 15/216,307, filed Jul. 21, 2016, and titled NEEDLELESS CONNECTOR AND ACCESS PORT DISINFECTION CLEANER AND ANTIMICROBIAL PROTECTION CAP, which is a continuation of U.S. patent application Ser. No. 13/766,540 filed Feb. 13, 2013, and titled NEEDLELESS CONNECTOR AND ACCESS PORT DISINFECTION CLEANER AND ANTIMICROBIAL PROTECTION CAP, which are incorporated herein by reference.

BACKGROUND OF THE INVENTION

Catheter-related bloodstream infections are caused by bacteria/fungi in patients with intravascular catheters. These infections are an important cause of illness and excess medical costs, as approximately 80,000 catheter-related bloodstream infections occur in U.S. intensive care units each year. In addition to the monetary costs, these infections are associated with anywhere from 2,400 to 20,000 deaths per year.

Guidelines from the Centers for Disease Control and Prevention describe various ways to limit catheter-related bloodstream infections in hospital, outpatient and home care settings. The guidelines address issues such as hand hygiene, catheter site care and admixture preparation. Despite these guidelines, catheter-related bloodstream infections continue to plague our healthcare system.

Protective caps incorporating various disinfectants and/or antimicrobial agents are one approach that has been implemented to prevent these infections at needleless connection points. While these caps are effective for long-term protection against pathogens, long-term exposure to the antimicrobial agent or disinfectant can cause damage to the needleless connection or access point of a medical device. In some instances, the antimicrobial agent is suspended in an alcohol solvent. The alcohol solvent used in the protective cap has been shown to cause device failure in many connector type devices. To prevent this damage, some protective caps are designed to permit the alcohol-base to evaporate from the protective cap. However, once the alcohol solvent has evaporated, the effectiveness of the protective cap is diminished.

Therefore, there is a need for an effective and inexpensive way to reduce the number of catheter-related infections for needleless connectors and access ports. Such methods and systems are disclosed herein.

BRIEF SUMMARY OF THE INVENTION

In some implementations, a protective cap is provided for antiseptically maintaining a patient fluid line access valve (i.e. access valve) or a needleless connector. In some instances, a protective cap is provided having a first cap that is removable coupled to a second cap, wherein the first cap

has a first opening comprising a cavity in which is disposed a first pad. The first cap further comprises a coupling feature for receiving the second cap.

The second cap further includes a second opening having a cavity in which is disposed a second pad. The second opening further includes a compatible coupling feature whereby to receive or otherwise interconnect with the coupling feature of the first cap. The first and second caps each contain an antimicrobial composition that is configured to clean a needleless connector and/or an access port of an infusion system, such as an intravenous catheter assembly or intravenous tubing. In some implementations, the first opening of the first cap is temporarily sealed with a lid to prevent contamination and evaporation of the antimicrobial composition stored within the first pad. Further, in some instances the connection between the coupling features to the first and second caps prevents contamination of the second pad prior to use.

Some implementations of the present invention further include a protective cap system having a first and second cap that are independently coupled to different surfaces of an infusion device, such as a syringe. The first and second caps are independently removed from the syringe and applied to various surfaces to achieve short-term and long-term antimicrobial protection to various components of an infusion system.

Some implementations of the present invention further include a strip having a plurality of holes or openings for temporarily storing and organizing a plurality of protective caps. The protective caps comprise a first cap and a second cap, wherein each cap is configured to provide short-term and/or long-term antimicrobial protection to various components of an infusion system. In some instances, the openings of the first and second caps are sealed to a strip, rather than being inserted through an opening or hole.

BRIEF DESCRIPTION OF THE SEVERAL VIEWS OF THE DRAWINGS

In order that the manner in which the above-recited and other features and advantages of the invention are obtained will be readily understood, a more particular description of the invention briefly described above will be rendered by reference to specific embodiments thereof which are illustrated in the appended drawings. These drawings depict only typical embodiments of the invention and are not therefore to be considered to limit the scope of the invention.

FIG. 1A shows a protective cap device having a first cap threadedly coupled to a second cap in accordance with a representative embodiment of the present invention; FIG. 1B shows a cross-sectional view of the protective cap device of FIG. 1A in accordance with a representative embodiment of the present invention.

FIG. 2A shows a protective cap device having a first cap unthreaded from a second cap in accordance with a representative embodiment of the present invention; FIG. 2B shows a cross-sectional view of the protective cap device of FIG. 2A in accordance with a representative embodiment of the present invention.

FIG. 3 shows a cross-section view of a protective cap device having a first cap mechanically coupled to a second cap in accordance with a representative embodiment of the present invention.

FIG. 4A shows a needleless device fitted with a protective cap device having a first cap coupled to a nozzle of the needleless device, and a second cap stored on plunger of the needleless device in accordance with a representative

embodiment of the present invention; FIG. 4B shows a cross-sectional view of the needleless device fitted with the protective cap device of FIG. 4A in accordance with a representative embodiment of the present invention.

FIG. 5A shows perspective and detailed views of a plurality of protective caps arranged on a strip for conveniently providing multiple caps for use in protecting a needleless connector in accordance with a representative embodiment of the present invention; FIG. 5B shows a detailed perspective view of the plurality of protective caps arranged on the strip of FIG. 5A in accordance with a representative embodiment of the present invention.

DETAILED DESCRIPTION OF THE INVENTION

The presently preferred embodiment of the present invention will be best understood by reference to the drawings, wherein like reference numbers indicate identical or functionally similar elements. It will be readily understood that the components of the present invention, as generally described and illustrated in the figures herein, could be arranged and designed in a wide variety of different configurations. Thus, the following more detailed description, as represented in the figures, is not intended to limit the scope of the invention as claimed, but is merely representative of presently preferred embodiments of the invention.

Referring now to FIGS. 1A and 1B, a protective cap 10 is shown. Generally, protective cap 10 comprises a first cap 20 that is coupled to a second cap 40. Each cap 20 and 40 is configured to receive or otherwise couple to a needleless connector or access port of a component of an infusion system. In some instances, first cap 20 is configured to receive a needleless connector without being attached to the needleless connector long-term. For example, first cap 20 may be used to quickly clean a needleless connector just prior to the needleless connector being coupled to a second medical device. In other instances, second cap 40 is configured to be attached to a needleless connector for long-term protection. For example, in some embodiments second cap 40 comprises a set of threads or other feature for securely receiving and retaining a portion of a needleless connector.

In some embodiments, first and second caps 20 and 40 are separated and applied to a needleless connector or access port to prevent pathogens from colonizing thereon. Further, in some embodiments first cap 20 is temporarily applied to a needleless connector or access port to kill any pathogens present thereon. The first cap 20 is then removed from the needleless connector or access port and the port is connected to, or accessed with a component of an infusion system. Upon removal of the component of the infusion system, first cap 20 is removed from second cap 40, and second cap 40 is fixedly coupled to the needleless connector or access port for long-term protection.

Protective cap 10 may comprise any material that is compatible for use in an infusion system. For example, in some embodiments protective cap comprises any of a number of types of plastic materials such as polycarbonate, polypropylene, polyethylene, glycol-modified polyethylene terephthalate, acrylonitrile butadiene styrene or any other moldable plastic material used in medical devices.

In some embodiments, first cap 20 and second cap 40 are selectively coupled to form protective cap 10. For example, in some embodiments first cap 20 comprises a set of threads 22 that is configured to interlock with a set of mating threads 42 on second cap 40. In some instances, first cap 20 comprises a post 24 that supports threads 22 in a configu-

ration that permits an opening 46 of second cap 40 to receive post 24 and threads 22. In some instances, mating threads 42 comprises a set of female threads that are formed into an inner surface 44 of second opening 46. Other embodiments include a cavity (not shown) on first cap 20 having internal threads and a width sufficient to receive external threads (not shown) located on an outer surface of second cap 40.

First cap 20 further comprises a first opening 28 having a first pad 30 disposed therein. First pad 30 generally comprises an absorbent material, such as a sponge or other non-woven material. In some instances, first pad 30 comprises an absorbent, woven material. First pad 30 may be secured into first opening by mechanical interference. Alternatively, first pad 30 may be secured into first opening 28 via a biocompatible adhesive.

In some instances, first pad 30 further comprises a central, cylindrical cutout 32 that is not directly, physically coupled to the inner surface of opening 28. Rather, cutout 32 may be collapsed or compressed to provide a central hole or cavity within first pad 30. For example, cutout 32 may be compressed by inserting a device into opening 28, such as needleless connector or access port. In this way, a tip and sides of the inserted device may be simultaneously contacted by first pad 30 without disrupting the bond between first pad 30 and the inner surface of second opening 28.

Second cap 40 further comprises a second pad 48 that is fixedly seated into second opening 46. Second pad 48 generally comprises a woven or non-woven absorbent material, such as a sponge. In some embodiments, second pad 48 is positioned within second opening 46 so that second pad 48 does not contact post 24 when first cap 20 is threadedly coupled to second cap 40. In other embodiments, second pad 48 is compressed within second opening 46 by post 24 when first cap 20 is threadedly coupled to second cap 40. Upon separation of first and second caps 20 and 40, second pad 48 is uncompressed and expands such that second pad 48 contacts and/or overlaps threads 42. This feature may be desirable for treating threads 42 with an antimicrobial composition stored in second pad 48.

First and second pads 30 and 48 may comprise an antimicrobial composition that is effective in preventing growth and colonization of pathogens, and that is safe for use in an infusion system. An antimicrobial composition in accordance with the present invention generally comprises an antimicrobial or biocidal agent effective against various forms and strains of bacteria which may cause infection within a patient. The terms "biocidal agent" "antimicrobial agent" or "biocide," as used herein refer to an agent that destroys, inhibits and/or prevents the propagation, growth, colonization and multiplication of unwanted organisms. The term "organism" includes, but is not limited to, microorganisms, bacteria, undulating bacteria, spirochetes, spores, spore-forming organisms, gram-negative organisms, gram-positive organisms, yeasts, fungi, molds, viruses, aerobic organisms, anaerobic organisms and mycobacteria.

Specific examples of such organisms include the fungi *Aspergillus niger*, *Aspergillus flavus*, *Rhizopus nigricans*, *Cladosporium herbarium*, *Epidermophyton floccosum*, *Trichophyton mentagrophytes*, *Histoplasma capsulatum*, and the like; bacteria such as *Pseudomonas aeruginosa*, *Escherichia coli*, *Proteus vulgaris*, *Staphylococcus aureus*, *Staphylococcus epidermidis*, *Streptococcus faecalis*, *Klebsiella*, *Enterobacter aerogenes*, *Proteus mirabilis*, other gram-negative bacteria and other gram-positive bacteria, mycobactin and the like; and yeast such as *Saccharomyces cerevisiae*, *Candida albicans*, and the like. Additionally,

spores of microorganisms, viruses and the like are organisms within the scope of the present invention.

Antimicrobial or biocide agents suitable for use in the present invention include, but are not limited to phenol, quaternary ammonium, guanidine, taurolidine, parachloro-metaxylenol, silver sulfadiazine, silver oxide, silver nitrate, pyridinium, benzalkonium chloride, cetrimide, benzethonium chloride, cetylpyridinium chloride, dequalinium acetate, dequalinium chloride, and chloroxylenol. Further, in some embodiments a biocide agent comprises a microbial agent selected from chlorhexidine base, chlorhexidine gluconate, chlorhexidine acetate, chlorhexidine hydrochloride, chlorhexidine dihydrochloride, dibromopropamide, halogenated diphenylalkanes, carbanilide, salicylanilide, tetrachlorosalicylanilide, trichlorocarbanilide, and mixtures thereof. Still further, in some embodiments a biocide agent comprises a microbial agent selected from chlorhexidine dihydrochloride, chlorhexidine gluconate, chlorhexidine acetate, chlorhexidine diacetate, triclosan, chloroxylenol, dequalinium chloride, benzethonium chloride, benzalkonium chloride, and combinations thereof.

In some embodiments first or second pads 30 and 48 comprise a liquid antimicrobial composition. In other embodiments, first or second pads 30 and 48 comprise a dehydrated antimicrobial composition, wherein the dehydrated antimicrobial composition is activated upon rehydration with a fluid, such as water, alcohol, blood, or another liquid common to infusion therapies. In some instances, lid 50 provides a fluid tight seal for first opening 28, thereby preventing premature evaporation of an antimicrobial composition stored in first pad 30. Further still, in some instances interlocked threads 42 and 22 provide a fluid tight seal for second opening 46, thereby preventing premature evaporation of an antimicrobial composition stored in second pad 48.

In some embodiments, first pad 30 comprises a liquid antimicrobial composition, wherein lid 50 prevents premature evaporation of the antimicrobial agent prior to use. In other embodiments, second pad 48 comprises a dehydrated antimicrobial composition, wherein the dehydrated antimicrobial composition is activated upon rehydration with a fluid, such as water, alcohol, blood, or another liquid common to infusion therapies. In some instances, the dehydrated state of second pad 48 prevents long-term exposure of the needleless connector to a liquid, alcohol-based antimicrobial composition. Contact between a dehydrated composition within second pad 48 and the surface of the needleless connector provides antimicrobial protection without causing damage thereto. As such, damage to the needleless connector caused by a liquid, alcohol-based antimicrobial composition is prevented. Further, the dehydrated state of the second pad 48 wicks or removes fluids from the needleless connector, thereby preventing damage and/or colonization of microbes on the needleless connector. Once wicked into second pad 48, the dehydrated antimicrobial agent is activated and microbes within the fluid are neutralized.

In some instances, first and second pads 30 and 48 each comprise an identical antimicrobial composition. In other instances, first pad 30 comprises a first antimicrobial composition, and second pad 48 comprises a second antimicrobial composition, wherein the first and second antimicrobial compositions are different. Thus, first cap 20 may be used to provide a first type of disinfection, and second cap 40 may be used to provide a second type of disinfection.

Prior to use, first and second caps 20 and 40 are threadedly coupled together and first opening 28 is sealed with a lid 50, such as a piece of foil, a thin polymer membrane, a foil-

backed piece of paper, or a polymer-backed piece of paper. To use protective cap 10, a user may remove lid 50 to expose first pad 30 seated in first opening 28. A user may insert an access valve or a needleless connector into first opening 28 and into contact with first pad 30. The access valve or needleless connector is treated with the antimicrobial composition as the surfaces are contacted with first pad 30.

Once the access valve or needleless connector is cleaned, it may be connected to another component of an infusion system. Upon disconnecting the access valve or needleless connector, second cap 40 is removed or unthreaded from first cap 20, as shown in FIGS. 2A and 2B. Second cap 40 is attached to the disconnected valve or connector to provide antimicrobial protection thereto during long-term storage.

For example, in some embodiments the access valve or needleless connector comprises a set of threads that are compatibly received by the set of mating threads 42 located on inner surface 44 of second cap 40. When second cap 40 is threadedly connected to the valve or connector, second pad 48 contacts the valve or connector to provide antimicrobial cleaning and protection. The threaded connection between second cap 40 and the access valve or connector further prevents exposure of the needleless connector to microbes or other contaminants. In some instances, the threaded connection prevents exposure to fluids which may leak from the valve or connector.

Referring now to FIG. 3, first and second caps 20 and 40 may be selectively coupled by any means. For example, in some embodiments post 24 of first cap 20 comprises an annular ring 26 that snaps into an annular groove 45 that is formed on inner surface 44 of second cap 40. The interaction between ring 26 and groove 45 provide a mechanical connection that may be separated by pulling apart the first and second caps 20 and 40. Ring 26 and groove 45 further provide a fluid tight seal, thereby preventing evaporation of an antimicrobial composition stored in second pad 48.

In some instances, an access valve or needleless connection further comprises an annular ring that is compatibly received by annular groove 45 when second cap 40 is placed thereon. In other embodiments, second cap 40 is retained by the access valve or needleless connection via mechanical interference or friction fit.

In some embodiments, a protective cap comprising a set of individual caps may be configured for attachment to a pre-filled syringe 100, as shown in FIGS. 4A and 4B. In some instances it is desirable to provide a syringe 100 that is pre-filled with a desired liquid 102. In these instances, it is further desirable that the liquid 102 and the needleless connector or nozzle 104 remain free from pathogens before and during use.

Accordingly, in some embodiments a first cap 120 is provided having a receptacle 122 for receiving nozzle 104 of syringe 100. Prior to capping nozzle 104 with receptacle 122 of first cap 120, receptacle 122 is sterilized. This prevents contamination of nozzle 104 and fluid 102, as may be desired. Sterilization of receptacle 122 may be achieved by any known method in the art.

First cap 120 further comprises a second receptacle 128 formed by an inner wall 128a and a sidewall 128b. The inner wall 128a is a flat surface that forms a full circle and from which the sidewall 128b extends perpendicularly. The sidewall 128b has a circular cross-sectional shape and defines an inner diameter of the second receptacle 128. A first pad 130 is seated within the second receptacle 128. The first pad 130 includes an inner surface 130a, a side surface 130b, and an outer surface 130c. The inner surface 130a is a flat surface that forms a full circle that corresponds with the flat surface

of the inner wall 128a and is secured to the inner wall 128a. The side surface 130b has a circular cross-sectional shape from the inner surface 130a to the outer surface 130c that corresponds with the circular cross-sectional shape of the sidewall 128b and is secured to the sidewall 128b. The outer surface 130c includes a planar surface having a diameter equal to a distance between a first side of the circular cross-sectional shape of the sidewall 128b and a second side of the circular cross-sectional shape of the sidewall 128b opposite the first side of the circular cross-sectional shape of the sidewall 128b. The outer surface 130c forms a full circle and is oriented towards an opening 128c of the second receptacle 128. The full circle of the outer surface 130c extends parallel to the flat surface of the inner wall 128a. A cutout 132 may be formed into the outer surface 130c to divide the first pad 130 into a central, cylindrical cutout and a surrounding portion. The central cylindrical cutout may be collapsed or compressed to provide a central hole or cavity within the first pad 130. The sidewall 128b may be flared at the opening 128c. First pad 130 may comprise an antimicrobial composition that is configured to clean an access port (not shown) intended to receive nozzle 104 of syringe 100. First cap 120 may further include a lid 150 to protect first pad 130 and prevent evaporation of the antimicrobial composition prior to use.

The protective cap may further include a second cap 140 that is removable coupled to a portion of syringe 100. For example, in some embodiments cap 140 is coupled to the plunger 106 of syringe 100. Plunger 106 may comprise a circular groove 107 that is configured to receive and temporarily store second cap 140. In some embodiments, second cap 140 is threadedly secured to plunger 106. In other embodiments, second cap 140 is coupled to plunger 106 via a friction fit.

The connection between second cap 140 and syringe 100 prevents evaporation and/or contamination of an antimicrobial agent stored in second cap 140. For example, in some instances second cap 140 comprises a second pad 148 containing an antimicrobial composition. The connection between second cap 140 and syringe 100 provides a fluid tight seal for second pad 148. The connection between second cap 140 and syringe 100 further provides convenient placement of second cap 140 for access by a user of the syringe.

For example, in some embodiments a user of syringe 100 first removes lid 150 from first cap 120 to expose first pad 130. First pad 130 is then used to clean an access port of an infusion system. The access port is clean by inserting the access portion within second opening 128 to contact first pad 130. First cap 120 is then removed from nozzle 104. Nozzle 104 is then connected to the access port.

In some instances, a desired volume of fluid 102 is injected into the infusion system via an access port. Where the desired volume comprises the entire contents of syringe 100, second cap 140 may be removed from plunger 106 following injection of liquid 102, and connected to the access port to prevent subsequent contamination thereof. Where the desired volume comprises only a portion of the contents of syringe 100, and where it is desirable to use the remaining contents of syringe 100 at a later time, second cap 140 may be removed from plunger 106 and coupled to nozzle 104 to prevent subsequent contamination thereof. Second cap 140 further prevents contamination of the remaining fluid 102. At the time in which it is desirable to inject the remaining fluid 102 into the access port, second cap 140 is removed from nozzle 104 and is used to clean the access port. The clean nozzle 104 is then inserted into the

clean access port, and the remaining fluid is injected without introducing microbes into the infusion system. In some embodiments, second cap 140 is then coupled to the access port to provide long-term antimicrobial protection.

Referring now to FIGS. 5A and 5B, a plurality of protective caps 10 is provided on a strip 200 that is configured to be removable coupled to a medical device, such as an IV stand 210. This configuration may be desirable for situations where a needless connector 220 may require repeated cleanings over a period of use. In some embodiments, strip 200 comprises a plurality of holes or openings 202 through which each cap is fitted. In some instances, each cap comprises a first cap 20 and a second cap 40, wherein strip 200 is inserted between the two caps.

In some instances, cap 10 is removed from strip 200 by separating first cap 20 from second cap 40. In other instances, cap 10 is removed from strip 200 by stretching or biasing opening 202 via pushing or pulling cap 10. First and second caps 20 and 40 may be used to clean needless connector 220, in accordance with the teachings above. Upon subsequent cleanings, the first and second caps of a first protective cap are discarded and an additional protective cap is removed from strip 200 and used. An enlarged opening 206 may be provided to assist in coupling strip 200 to a desired medical device 210. In some embodiments, strip 200 is temporarily secured to a medical device via an adhesive strip or other suitable means.

The present invention may be embodied in other specific forms without departing from its structures, methods, or other essential characteristics as broadly described herein and claimed hereinafter. The described embodiments are to be considered in all respects only as illustrative, and not restrictive. The scope of the invention is, therefore, indicated by the appended claims, rather than by the foregoing description. All changes that come within the meaning and range of equivalency of the claims are to be embraced within their scope.

The invention claimed is:

1. A device for antisceptically maintaining a patient fluid line access valve, the device comprising:
a syringe, comprising a nozzle;
a cap, comprising:
a first receptacle coupled to the nozzle, the first receptacle being formed by a first inner wall and a first sidewall, wherein the first inner wall is a first flat surface that forms a full circle at a first end of the first receptacle, the first sidewall extending from the first inner wall to a second end of the first receptacle, the second end of the first receptacle forming an opening of the first receptacle, and wherein the first sidewall has a circular cross-sectional shape between the first inner wall and the second end of the first receptacle, wherein a diameter of the circular cross-sectional shape of the first sidewall remains the same from the first inner wall to the second end of the first receptacle, and wherein the diameter of the circular cross-sectional shape of the first sidewall substantially matches a diameter of the nozzle of the syringe such that the cap is coupled to the syringe by inserting the nozzle into the first receptacle through the opening of the first receptacle;
a second receptacle opposite the first receptacle, the second receptacle being formed by a second inner wall and a second sidewall, wherein the second inner wall is a second flat surface that forms a full circle at a first end of the second receptacle, the second sidewall extending from the second inner wall to a second end of the second receptacle, the second end of the second receptacle forming an opening of the second receptacle, and wherein the second sidewall has a circular cross-sectional shape between the second inner wall and the second end of the second receptacle, wherein a diameter of the circular cross-sectional shape of the second sidewall remains the same from the second inner wall to the second end of the second receptacle, and wherein the diameter of the circular cross-sectional shape of the second sidewall substantially matches a diameter of the nozzle of the syringe such that the cap is coupled to the syringe by inserting the nozzle into the second receptacle through the opening of the second receptacle;

of the second receptacle, the second end of the second receptacle being positioned at a first distance from the second inner wall, and wherein the second sidewall has a circular cross-sectional shape between the second inner wall and the second end of the second receptacle, wherein a diameter of the circular cross-sectional shape of the second sidewall remains the same from the second inner wall to a second distance from the second inner wall, the second distance being less than the first distance, and the diameter of the circular cross-sectional shape of the second sidewall increases linearly from the second distance to the second end of the second receptacle to thereby cause the opening of the second receptacle to be flared, wherein the diameter of the circular cross-sectional shape of the second sidewall between the second inner wall and the second distance matches the diameter of the circular cross-sectional shape of the first sidewall; and

a first pad seated within the second receptacle, the first pad having an inner surface, a side surface and an outer surface, wherein the inner surface is a flat surface that forms a full circle that corresponds with the second flat surface of the second inner wall, wherein the side surface has a circular cross-sectional shape from the inner surface to the outer surface that corresponds with the circular cross-sectional shape of the second sidewall, wherein the outer surface comprises a planar circular surface, wherein the planar circular surface and the circular cross-sectional shape of the side surface between the inner surface to the outer surface have a diameter substantially matching the diameter of the circular cross-sectional shape of the second sidewall between the second inner wall and the second distance, wherein the outer surface is positioned at a third distance from the second inner wall, the third distance being less than the second distance, wherein the outer surface is oriented towards the opening of the second receptacle such that the planar circular surface is configured to contact and clean an access port when the access port is inserted into the opening of the second receptacle, wherein the first pad comprises an antimicrobial solution.

2. The device of claim 1, wherein a cylindrical cut extends into the outer surface to divide the first pad into a central, cylindrical cutout and a surrounding portion, wherein the central, cylindrical cutout is aligned with a central axis of the cap.

3. The device of claim 2, wherein when a device is inserted into the second receptacle, the central, cylindrical cutout compresses to displace a portion of the outer surface on the central, cylindrical cutout from another portion of the outer surface on the surrounding portion thereby forming a central cavity within the first pad.

4. The device of claim 1, further comprising a removable lid covering the opening of the second receptacle.

5. The device of claim 4, wherein the removable lid comprises at least one of a foil lidding material and a polymer lidding material.

6. The device of claim 1, wherein the syringe comprises a plunger aligned with a central axis of the first and second receptacles.

7. The device of claim 1, wherein the syringe is pre-filled with a liquid.

8. The device of claim 1, wherein the antimicrobial solution comprises a wet solution selected from at least one of an antimicrobial agent from approximately 0.01% to

approximately 10.0% (v/v) and an alcohol from approximately 50% to approximately 99.99% (v/v).

9. The device of claim 8, wherein the antimicrobial agent is selected from the group consisting of chlorhexidine acetate, chlorhexidine gluconate, and Triclosan.

10. The device of claim 1, wherein the antimicrobial solution comprises a wet, water-based solution, comprising: an antimicrobial agent from approximately 0.01% to approximately 10.0% (v/v); an alcohol solvent from approximately 1% to approximately 10% (v/v); and water from approximately 90% to approximately 99% (v/v).

11. A device for antiseptically maintaining a patient fluid line access valve, the device comprising: a syringe, comprising a nozzle and a plunger; a first cap, comprising:

a first receptacle coupled to the nozzle, the first receptacle being formed by a first inner wall and a first sidewall, wherein the first inner wall is a first flat surface that forms a full circle at a first end of the first receptacle, the first sidewall extending from the first inner wall to a second end of the first receptacle, the second end of the first receptacle forming an opening of the first receptacle, and wherein the first sidewall has a circular cross-sectional shape between the first inner wall and the second end of the first receptacle, wherein a diameter of the circular cross-sectional shape of the first sidewall remains the same from the first inner wall to the second end of the first receptacle, and wherein the diameter of the circular cross-sectional shape of the first sidewall substantially matches a diameter of the nozzle of the syringe such that the first cap is coupled to the syringe by inserting the nozzle into the first receptacle through the opening of the first receptacle;

a second receptacle opposite the first receptacle, the second receptacle being formed by a second inner wall and a second sidewall, wherein the second inner wall is a second flat surface that forms a full circle at a first end of the second receptacle, the second sidewall extending from the second inner wall to a second end of the second receptacle, the second end forming an opening of the second receptacle, the second end of the second receptacle being positioned at a first distance from the second inner wall, and wherein the second sidewall has a circular cross-sectional shape between the second inner wall and the second end of the second receptacle, wherein a diameter of the circular cross-sectional shape of the second sidewall remains the same from the second inner wall to a second distance from the second inner wall, the second distance being less than the first distance, and the diameter of the circular cross-sectional shape of the second sidewall increases linearly from the second distance to the second end of the second receptacle to thereby cause the opening of the second receptacle to be flared, wherein the diameter of the circular cross-sectional shape of the second sidewall between the second inner wall and the second distance matches the diameter of the circular cross-sectional shape of the first sidewall; and

a first pad seated within the second receptacle, the first pad having an inner surface, a side surface and an outer surface, wherein the inner surface is a flat surface that forms a full circle that corresponds with

11

the second flat surface of the second inner wall, wherein the side surface has a circular cross-sectional shape from the inner surface to the outer surface that corresponds with the circular cross-sectional shape of the second sidewall, wherein the outer surface comprises a planar circular surface, wherein the planar circular surface and the circular cross-sectional shape of the side surface between the inner surface to the outer surface have a diameter substantially matching the diameter of the circular cross-sectional shape of the second sidewall between the second inner wall and the second distance, wherein the outer surface is positioned at a third distance from the second inner wall, the third distance being less than the second distance, wherein the outer surface is oriented towards the opening of the second receptacle such that the planar circular surface is configured to contact and clean an access port when the access port is inserted into the opening of the second receptacle, wherein the first pad comprises an antimicrobial solution; and

a second cap that is removably coupled to the plunger of the syringe, the second cap forming a third recep-

12

tacle, the third receptacle being formed by a third inner wall and a third sidewall, wherein the third inner wall is a third flat surface that forms a full circle at a first end of the third receptacle, the third sidewall extending from the third inner wall to a second end of the third receptacle, the second end of the third receptacle forming an opening of the third receptacle, and wherein the third sidewall has a circular cross-sectional shape between the third inner wall and the second end of the third receptacle, wherein a diameter of the circular cross-sectional shape of the third sidewall remains the same from the third inner wall to the second end of the third receptacle, and wherein the diameter of the circular cross-sectional shape of the third sidewall substantially matches the diameter of the nozzle of the syringe such that the second cap is coupled to the syringe by inserting the nozzle into the third receptacle through the opening of the third receptacle, the second cap further comprising a second pad seated within the third receptacle, the second pad comprising an antimicrobial solution.
